UNITED STATES PATENT OFFICE

RAYMOND W. COLE, OF CRANFORD, NEW JERSEY, ASSIGNOR TO CORDLEY & HAYES,
OF NEW YORK, N. Y., A CORPORATION OF NEW YORK

DESIGN FOR A DISPENSER

Application filed February 25, 1933. Serial No. 47,319. Term of patent 7 years.

To all whom it may concern:

Be it known that I, RAYMOND W. COLE, a citizen of the United States, residing at Cranford, in the county of Union and State of New Jersey, have invented a new, original, and ornamental Design for a Dispenser, of which the following is a specification, reference being had to the accompanying drawing, forming a part hereof, in which:

Figure 1 is a side elevation of a dispenser embodying my new design;

Figure 2 is a partial plan view of the dispenser, and

Figure 3 is a partial, horizontal section through the dispenser along the line 3—3 of Figure 1.

In the drawing the lower portion of the dispenser is lined to indicate mirrored surfaces along the sides.

I claim:

The ornamental design for a dispenser as shown and described.

RAYMOND W. COLE.
